UNITED STATES PATENT OFFICE

2,457,265

HIGH-TEMPERATURE FAN

Carl Nygren, Michigan City, Ind., assignor to
Michiganana Products Corporation, a corporation
of Indiana

Application April 24, 1947, Serial No. 743,516

7 Claims. (Cl. 230—134)

1

This invention relates to centrifugal fans or blowers for heat treating furnaces and has for its principal object to provide an improved arrangement and assembly of hub members and blades whereby the latter are securely made fast against outward movement under centrifugal force and against turning movements with respect to the hub members that will safely endure the rigorous conditions of service at high speed and high temperatures.

Generally speaking, this is accomplished by providing the blades with spaced legs which straddle a hub member having outwardly opening notches receiving the converging inner portions of the blades to effect a driving connection, and a circular series of fastening means, such as pins, make the legs fast to the hub member and also center the shroud members.

Fig. 1 is a front view of a double inlet fan with the upper portion shown in section;

Fig. 2 is a side elevation of a double inlet fan, portions of the side pieces and blades being broken away;

Fig. 3 is a perspective view of the central hub member;

Fig. 4 is a perspective view of one of twelve blades used in the double inlet fan;

Fig. 5 is a perspective view of one of 24 fastening pins;

Fig. 6 is a perspective view of one of two hub collars;

Fig. 7 is a perspective view of one of two open side plates used in the double inlet fan;

Fig. 8 is a perspective view of a closed side plate, one of which, together with one of the plates shown in Fig. 7, is used in a single inlet fan;

Fig. 9 is a view corresponding to Fig. 1 of a single inlet fan;

Fig. 10 is an end view of the hub member used in the single inlet fan;

Fig. 11 is a view of one of two collars used in the single inlet fan;

Fig. 12 is a view corresponding to Fig. 2 of the single inlet fan;

Fig. 13 is a perspective view of one of twelve blades used in the single inlet fan; and

Fig. 14 is a perspective view of one of 24 pins used in the single inlet fan.

In the drawings, 10 indicates a hollow water cooled shaft for supporting and driving the fan.

A hub member, generally indicated by 11 in Fig. 3, is secured to the shaft by three keys fitted in key-ways 12 in the bore of the hub and corresponding key-ways in the shaft. Each hub member has an intermediate rounded flange 14 provided with notches 15 to receive the machined portions 16 of the blades (Fig. 4) and form a driving connection with them.

In order to reduce the weight of the hub, its

2

diameter is reduced, as indicated at 17, at each side of the intermediate flange 14, and this results in end flanges 18, each of which has 12 pin holes 19 arranged in circular series to receive pins 20 (Fig. 5) for securing the blades and side plates to the hub member 11.

Each blade (Fig. 4) has a body portion 21 generally flat and rectangular in shape, and integral with it at the inner portion are legs 22 strengthened by gussets 23 and provided with pin holes 24 to receive pins 20.

Adjacent to their outer portions, each blade 21 has an overhanging hook 25 outwardly from machine faces 26, and these cooperate with the periphery of open side plates 27 (Fig. 7), which have notches 28 to receive the intermediate portions 29 of the hooks 25.

Each open side plate 27 is provided with openings 30 to provide inlets for the fan, which leaves spokes 31 connecting the peripheral shroud portions 32 with hub rings 33. The latter have twelve pin holes 34 to receive the pins 20 (Fig. 5).

The shaft 10 has a shoulder 35 against which one of two collars 36 (Fig. 6) is seated. The other collar 36 receives the thrust of a nut 37 threaded onto the shaft 10 and made fast by lock nut 38 and lock washer 39.

From this description and the drawings, it will be apparent that the blades 21 straddle the hub member 11 with their pin holes 24 aligned with pin holes 19. The side plates 27 are on the outer sides of the blades and interengaged with the hooks 25, and have the pin holes 34 aligned with the pin holes 24 and 19.

The collars 36 are on the opposite sides of the wheel outside of the side plates 27, and their reduced pin holes 40 receive the reduced portions 41 of the pins 20 (Fig. 5).

The single inlet fan construction is similar in all respects, except that the blades 51 (Fig. 13), hubs 52 (Fig. 10), and shaft 61 (Fig. 9) are shorter. One side plate 62 (Fig. 8) has no openings corresponding to those shown at 30 (Fig. 7).

In the fan construction shown in the patents to Nygren No. 2,385,838 and Williams No. 2,147,005, a fan of 18 inches in diameter or less has so much machining that it throws the cost of production out of line and really makes fans of those sizes too costly.

With the construction here illustrated, the machining is confined to small faces on the legs of the blades, which can be done with a gang machine; the blade slots and the hub flanges, which can be done with an automatic machine; and the pads 16 on the blades, which can also be done with a gang machine. Those machined surfaces are all small as compared with the prior constructions referred to.

The principal object of the present construction is to maintain the dynamic relation between

the hub member and the blades on a circular arrangement about the axis of rotation while leaving the outer portions free to expand and contract, but to reduce the unavoidable machining greatly, and therefore the cost.

The arrangement of the pins in the hubs, the legs of the blades, the side pieces forming the shrouds, and the collars establishes the dynamic relation between the parts that changes very little due to expansion and contraction. The nuts holding the collars in place are set up hard and then turned back an amount corresponding to the temperature at which the fan is to be used. For instance, in a 15-inch fan for working temperature up to 1600 degrees, the nut 36 should be turned back about $10/1000$ " at room temperature to allow for expansion.

In the construction shown in Nygren Patent No. 2,385,838, the shrouds are carried by the blades. The present construction is distinguished from that by the shrouds being part of side plates centered on the hub by the pins that establish the dynamic balance.

The interlocking relation between the outer portions of the side plates maintains the shrouds and blades in appropriate relation with great freedom in expansion and contraction.

The drawings show a construction for 15-inch fans with the double fan $8\frac{1}{8}$ " wide at the periphery and the single fan $3\frac{3}{8}$ " wide at the periphery. The intermediate flanges 14 of the hub member are 7" in diameter and slots 15 are $\frac{1}{8}$ " wide plus .001 minus .000, and the pads 16 on the blades are $\frac{1}{8}$ " thick plus .000 minus .002. The pin holes 19 and 24 are $\frac{1}{2}$ " in diameter reamed to plus .001 minus .000. The pins are .498" in diameter plus .000 minus .001, and the reduced portions 41 are .436" in diameter plus .000 minus .001.

The side plates are made of $\frac{1}{8}$ " mill flat. The hooks 25 receive the edges with liberal clearance, and there is $\frac{1}{8}$ " clearance between the intermediate portions of the hooks and the bottoms of the notches 28.

The specific features in the corresponding showing of the drawings and the description are made for the purpose of fullness of disclosure in this particular embodiment, but are not intended to impose unnecessary limitations on the claims.

I claim:

1. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, and means in circular series about the axis for making the legs fast to hold the blades against individual bodily movement outwardly due to centrifugal force.

2. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, and means in circular series about the axis for making the legs fast to hold the blades against in-

dividual bodily movement outwardly due to centrifugal force.

3. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, and pins in circular series about the axis for making the legs fast to the hub member to hold the blades against individual bodily movement outwardly due to centrifugal force.

4. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, pins in circular series about the axis for making the legs fast to the hub member to hold the blades against individual bodily movement outwardly due to centrifugal force, and shrouds centered by said pins cooperating with the blades.

5. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, pins in circular series about the axis for making the legs fast to the hub member to hold the blades against individual bodily movement outwardly due to centrifugal force, and shrouds centered by said pins cooperating with the blades.

6. In a high temperature centrifugal fan, a plurality of blades in circular arrangement about a common axis of rotation with their outer portions diverging outwardly from said axis and their inner portions converging inwardly toward said axis and terminating in spaced legs, a hub member straddled by the legs and having outwardly opening notches receiving the converging inner ends of the blades to effect a driving connection with them, pins in circular series about the axis for making the legs fast to the hub member to hold the blades against individual bodily movement outwardly due to centrifugal force, shrouds centered by said pins and interlocked with the blades.

7. In a high temperature centrifugal fan, a plurality of blades in circular arrangement about a common axis of rotation with their outer portions diverging outwardly from said axis and their inner portions converging inwardly toward said axis and terminating in spaced legs, a hub member having notches receiving the converging inner portions of the blades to effect a driving connection with them, shrouds at each side of the blades, and means in circular series about the axis for making the legs fast to hold the blades against individual bodily movement outwardly due to centrifugal force and centering the shrouds.

CARL NYGREN.
